UNITED STATES PATENT OFFICE.

PHILIP J. DARLINGTON, OF PITTSBURGH, PENNSYLVANIA.

ROTARY MOTOR.

1,071,145.

Specification of Letters Patent. Patented Aug. 26, 1913.

Application filed February 15, 1907. Serial No. 357,479.

To all whom it may concern:

Be it known that I, PHILIP J. DARLINGTON, of Pittsburgh, Allegheny county, Pennsylvania, have invented a new and useful improvement in Rotary Motors and Pumps, of which the following is a full, clear, and exact description, reference being had to the accompanying drawings, forming part of this specification, in which—

10 Figure 1 is a longitudinal section of a motor embodying my invention; Fig. 2 is a section on the line II—II of Fig. 1; Fig. 3 is a view similar to Fig. 1, but with the cylinder rotated so that the plane of section 15 is about forty-five degrees different than the plane of the section of Fig. 1; Fig. 4 is a section on the line IV—IV of Fig. 3; Fig. 5 is a section on the line V—V of Fig. 3; Figs. 6 and 7 are detail views of the head; 20 and Fig. 8 is a diagram illustrating the invention.

My invention has relation to rotary motors or pumps, and is designed to provide a motor or pump having greater displacement and consequently greater power, (for size and weight), combined with low initial and running friction, and which is capable of easy starting, high speed, and great range of speed.

30 A further object is to provide a motor or pump of this character which shall be simple in its construction and composed of few parts, no springs being required in connection with the piston and blades.

35 The main feature of my invention consists in the use of a cylinder whose walls are approximately defined by a closed curve formed by the revolution of a figure of sensible dimensions, preferably a circle, around a center which is itself revolving about a second center in the same direction and at double the angular velocity of the figure, whereby a single blade passing completely through a slotted shaft can be used, and whereby said 45 blade can have its edges of sensible thickness and both edges of the blade will at all times maintain contact with the cylinder walls.

Other features of my invention consist 50 in the arrangement of the cylinder heads, the manner of securing them to the cylinder, and other novel features of construction.

In the drawings, 2 designates the cylinder of the motor, in which is an eccentrically located piston chamber 3. This chamber is of peculiar shape in cross-section, in

that its bore is approximately the same distance across in all directions when measured through a fixed eccentric point, which point is the center of the eccentrically arranged piston shaft 4. The curve which defines the interior wall of the cylinder I term a "rotocentric" curve, being a curve substantially such as is described by the movement of a point around a center, which center is revolving around a second center in the same direction, but at double the angular velocity of the first center. The exact nature of this curve will be understood by reference to the diagram of Fig. 8. Supposing the describing point to be carried by an arm *a* which turns upon the center *b*, which center is in turn rotating about the center *c*, it will be seen that when this describing point has moved from the position *d* to the position *e*, the center *b* will have moved to the point *b'* about the center *c*, making the angle *y* double the angle *x*. The center lines of the arm *a* in the two positions shown in the diagram will intersect at the point *b''*, which is the point occupied by the center *b* when it has traveled through one hundred and eighty degrees. When the center *b* has made a complete revolution from the point *e*, and has returned to that point, the describing point at the end of the arm *a* will have reached the point *f*, and the line *e, f* will pass through the point *b''*. It will be seen, therefore, that it is characteristic of the curve 55 generated by the describing point that it will inclose a point through which the figure will measure exactly the same distance in every direction, and that such point is the point *b''*. This curve, as will be seen 60 from the diagram, is somewhat heart-shaped in comparison with the inscribed circle *g*. In practice, the curve will be modified owing to the fact that the cutting tool instead of being a mere point is an edge of some thickness and definite form. From the foregoing, it will be readily seen that if the piston 65 blade 5 of the motor, having the same form of edge, be substituted for a tool of form *a* and be moved in a similar manner, it will 70 maintain contact with the cylinder at both edges throughout a complete revolution. The blade may be moved by any of several means, including that arrangement of gearing and eccentrics which was used to rotate 75 the tool in forming the cylinder.

For practical work it is essential that the

edges of the blade be of sensible thickness or dimension, and not a mere knife edge. Preferably the edges are formed on semi-circles, as shown.

My preferred construction is a blade 5 arranged to move freely through the slot 6 of the piston shaft 4, whose center corresponds with the point 3². As the piston 4 is rotated, both ends of the blade will maintain a contact with the cylinder wall throughout a complete revolution. The shaft 4 should be of such diameter as to contact with the wall of the cylinder at one side and make a fluid tight joint therewith as shown.

One end of the motor cylinder is closed by a head 7 which is preferably shouldered within the open end of the cylinder, while the other end of the cylinder is closed by a head 8 which is similarly shouldered within that end. The bore or piston chamber 3 is eccentric to the exterior of the cylinder and it also is not a true circle. Hence the ends of the cylinder are provided with circular counterbores, shown as concentric with the exterior of the cylinder, in which counterbores the circular shouldered ends of the heads are seated, as shown. These heads are turned to make a close fit with the cylinder, and the parts are secured together by means of the tension rods 9, having threaded ends which are engaged by nuts 10 and 11, the nuts 10 being seated in recesses 12 of the head 8 and having a bearing against the rear walls thereof, while the nuts 11 have a bearing against the rear end of the head 7. Instead, however, of employing nuts at both ends of these rods, it is evident that a fixed head may be formed at one end. The heads, together with the cylinder, are provided with open grooves 13, in which the rods 9 are seated.

The admission head 7 has an interior chamber 14, into which leads an inlet pipe 15, and which communicates with the longitudinal port 16 formed in the thickened cylinder wall through a port 17 in a plug 18 which is seated within the head 7, and which forms the front wall of the chamber 14. The port 16 communicates with the cylinder chamber by means of a plurality of cross-ports 19. The head 8 has therein an exhaust port 20 which communicates with a longitudinal exhaust port 21 in the cylinder wall, the latter communicating with the cylinder chamber by the series of cross-ports 22.

The piston shaft 4 is journaled in the plug 18 at one end portion, and in the head 8 at its opposite end portion, and is extended through said head for connection at 23 with the tool or shaft to which power is to be applied.

Although I have specifically described my invention in connection with a motor,

it will be obvious that the form of cylinder as shown and described is equally advantageous for use in pumps, it being immaterial whether the piston is operated by fluid admitted thereto under pressure, or whether the shaft 4 is rotated by external power to draw fluid into the piston chamber and exhaust it therefrom. It will be further apparent that a cylinder of this kind is capable of wide application in motors and pumps generally, and that this feature is not limited to the particular form of motor shown.

By the use of the cylinder such as described, a single piston blade only is required. This blade at all times has a full depth of bearing in the slotted shaft, which gives a blade extension, with consequent displacement and power, which is not possible where separate blades are employed. By reason of this wide bearing of the single blade in the slot of the shaft, there is very little friction of the blade either in the slot or on the cylinder walls. With the usual eccentric types, where each blade has, (at the time of greatest torque), a very shallow bearing in the shaft, the friction of the blade, both in the shaft and against the cylinder, is very large. This friction starts with the action of the blade spring, is increased by the centrifugal forces acting on the blade, and by the driving torque of the blade in the shaft, and the result is loss of power, limited speed, bad heating and rapid wear of both blades and cylinder. With the present invention, when running at high speed, the two halves of the single blade almost balance each other in centrifugal effort, and in consequence the pressure of the blade against the cylinder is in all positions small, and is nothing at the critical position represented by the line s, t in Fig. 8. As a result, the loss of power, generation of heat, and the wear of the blade and cylinder, is much less than is possible in motors with divided blades, in which the centrifugal force against the cylinder is equal to the sum of the two separate blades instead of the difference between the two halves of the single blade, as in the present case. Owing to the fact that no blade spring is employed, the initial friction is very small. These advantages have been fully confirmed by actual test, in which the results were both remarkable and satisfactory.

What I claim is:—

1. In a motor, a cylinder having longitudinally extending admission and exhaust ports, ported heads fitted to the ends of the cylinder, and tension rods connecting the heads, said heads and cylinder having seats for the said rods; substantially as described.
2. In a motor, a cylinder having a longitudinally extending admission port, a head at one end of the cylinder having an adminis-

- sion chamber therein, and a plug seated within the admission chamber and having a port therethrough which connects the chamber with the admission port of the cylinder; substantially as described.
3. In a rotary machine, a cylinder having a longitudinal piston chamber located eccentrically therein and having a circular counterbore in its end, and a head seating in said counterbore.
4. In a rotary machine, a cylinder having a longitudinal piston chamber located eccentrically therein and having in its end a circular counterbore concentric with its exterior, and a head seating in said counterbore.
5. In a rotary machine, a cylinder having a longitudinal piston chamber located eccentrically therein and having in its ends circular counterbores, heads seated in said counterbores, and tension rods connecting said heads.
6. In a rotary machine, a cylinder having a longitudinal piston chamber therein, heads closing the ends of said cylinder, and a piston shaft journaled in said heads, the rear end of said shaft being reduced and seated in the rear head and the front end of said shaft being of full diameter and projecting through the front head and being provided with means for the attachment of a tool.
7. In a motor, a cylinder having a longitudinally extending admission port, a head at one end of the cylinder having an admission chamber therein, and a bushing member seated within the admission chamber and having a bearing for the motor shaft, and also having a port therethrough which connects the chamber with the admission port of the cylinder; substantially as described.
8. In a motor, a cylinder having a longitudinally extending admission port, a head at one end of the cylinder having an admission chamber therein, a bushing seated within the admission chamber and having a port therethrough which connects the chamber with the admission port of the cylinder, and a piston shaft journaled at one end in said bushing and having a thrust collar at its rear end engaging said bushing; substantially as described.
9. In a motor, a cylinder having longitudinally extending admission and exhaust ports, ported heads fitted in the ends of said cylinder, a bushing member seated in one of said heads, and tension rods connecting the said heads and engaging the bushing member; substantially as described.

In testimony whereof, I have hereunto set my hand.

P. J. DARLINGTON.
